FIG. 4.

Clarence J. Huth,

BY

Richard D. Diven.

ATTORNEY

UNITED STATES PATENT OFFICE.

CLARENCE J. HUTH, OF NORTH BRANCH, NEW YORK.

WINDOW ATTACHMENT.

1,264,936.

Specification of Letters Patent.

Patented May 7, 1918.

Application filed December 4, 1917. Serial No. 205,401.

To all whom it may concern:

Be it known that I, CLARENCE J. HUTH, a citizen of the United States, residing at North Branch, in the county of Sullivan and 5 State of New York, have invented certain new and useful Improvements in Window Attachments, of which the following is a specification.

This invention relates to a window sash 10 fastener and has for its object the production of a simple and efficient sash fastener which will automatically fit under a sash and hold the sash in an open position when the same is raised. 15 Another object of this invention is a production of a simple and efficient automatic window sash lock which comprises a minimum number of parts, and which may be very cheaply and easily manufactured. 20 With these and other objects in view, this invention relates to certain novel construction, combinations and arrangement of parts as will be hereinafter fully described and claimed.

25 In the drawings:

Figure 1 is a side elevation of the sash lock in an open position,

Fig. 2 is a side elevation of the sash lock in a closed or locked position,

30 Fig. 3 is a section taken on line 3—3 of Fig. 1,

Fig. 4 is an edge elevation of the sash fastener.

By referring to the drawings it will be 35 seen that 1 designates a supporting plate which is adapted to be secured to a window frame or other suitable support by means of suitable securing pins 2. A sash 3 is carried by the frame of the window and an 40 automatic locking device is supported upon the supporting plate 1. This locking device comprising a locking block 3 which is provided with a substantially V-shaped sash engaging notch 4 upon the inner edge thereof. 45 The block 3 is pivotally mounted upon a pivot pin 5, the pivot pin 5 also extending through the roller carrying plates 6. These plates 6 are secured to the opposite faces of the block 3 and carry a friction roller 7 upon 50 their outer ends, which roller 7 is preferably formed of rubber or other resilient material, in this way preventing the window sash 3 from being injured by engagement thereof with the roller 7.

55 A spring engagement pin 8 is carried between the inner ends of the plates 6 and a

coiled spring 9 is secured to this pin 8 and is anchored upon the plate 1 by means of an anchoring pin 10.

The block 3 carries a projecting finger 11 60 which finger 11 carries a resilient buffer disk 12 which buffer disk 12 is adapted to engage the stop pin 13 carried by the plate 1 which stop pin 13 is provided with a resilient covering 14.

As shown in Figs. 1 and 2 a resilient strip 15 is carried by the outer end of the block 3 within the notch 4 and a resilient strip 16 is carried within the valley portion of the notch 4, in this way constituting an efficient 70 sash engaging buffer means for yieldably engaging the lower end of a window sash as shown in Fig. 2. The outer beveled edge 17 also carries a resilient buffer strip 18 for the purpose of preventing the window sash 75 3 from being injured as the block is swung into engaged relation with the window sash 3. The inward swinging movement of the block 3 will be limited by means of the projecting plate 11 coming into contact with 80 the stop 13. The spring 9 will hold the roller 7 in frictional engagement with the window sash and cause the block 3 to automatically engage the window sash 3' as soon as the window sash 3' is raised to an open 85 position.

From the foregoing description it will be seen that a very simple and efficient device has been produced in the nature of an automatic sash fastener, which device comprises 90 a minimum number of parts capable of being easily and quickly installed.

When it is desired to swing the body 3 to an open position, the operator may press downwardly upon the plate 11 and in this 95 way draw the notch 14 out of engagement with the window sash 3'.

What is claimed is:

1. A sash fastener comprising a body, said body provided with a sash engaging notch, 100 yieldable buffer means mounted within said notch, a plurality of crescent shaped plates secured to said body, the ends of said plates projecting beyond the side edges of said body, a friction roller carried by said plates, 105 a spring engaging the opposite ends of said plates with respect to said roller, and means for limiting the swing of said body in one direction.

2. A sash fastener comprising a body, a 110 sash engaging roller carried by said body near one side thereof and adapted to nor-

normally hold said body out of engagement with a sash, said body provided with sash engaging means adapted to firmly engage a sash when said sash engaging roller is thrown out of engagement with a sash, means for yieldably holding said sash engaging roller in an operative position, a stop plate projecting beyond the lower end of said body, a yieldable buffer carried by said plate, and a stop pin adapted to engage said yieldable buffer for limiting the swinging movement of said body.

3. A sash fastener of the class described comprising a body, said body provided with a substantially V-shaped notch upon one end thereof, a sash engaging roller carried by said body and adapted to normally hold said notch in an inoperative position, means for swinging said body as said roller is thrown out of engagement with a sash, and said substantially V-shaped notch adapted to fit over

the lower end of a sash for firmly supporting the same against sliding movement and also adapted to firmly hold a sash against rattling while the same is being held in an 25 adjusted position.

4. A sash fastener comprising a body, said body provided with a sash engaging notch formed therein, yieldable buffer means mounted within said notch, a plurality of 30 side plates carried by said body, the ends of said side plates projecting beyond the sides of said body, a friction roller carried by said plates, and means engaging the opposite ends of said plates for yieldably holding said 35 roller in engagement with a sash.

In testimony whereof I affix my signature in presence of two witnesses.

CLARENCE J. HUTH.
